UNITED STATES PATENT OFFICE.

ROBERT W. FERGUSON, OF DECATUR, ILLINOIS, ASSIGNOR TO WILLIAM B. CLARK AND FRAZIER W. NEVIUS, BOTH OF SAME PLACE.

IRONING-BOARD.

SPECIFICATION forming part of Letters Patent No. 292,904, dated February 5, 1884.

Application filed April 9, 1883. (No model.)

To all whom it may concern:

Be it known that I, ROBERT W. FERGUSON, a citizen of the United States, residing at Decatur, in the county of Macon and State of Illinois, have invented certain new and useful Improvements in Ironing-Boards, of which I declare the following to be a full, clear, and exact description.

My present invention has for its object to 10 provide an ironing-board of the class commonly known to the trade as "bosom-boards," with improved means whereby the shirt can be tightly stretched against the board during the ironing operation. This object of invention I have accomplished by the mechanism, 15 hereinafter described, illustrated in the accompanying drawings, and particularly defined in the claims at the end of this specification.

20 Figure 1 is a detail side view of one end of the board and the hinged flap and clamp-wire. Figs. 2 and 3 are respectively a side and a rear view of the board.

A designates the body of the board, which 25 may be of any desired length, preferably ten by eighteen inches, and which is suitably padded upon both its surfaces. In one end of this board are embedded the ends b of the wire springs B, which constitute the collar-band 30 stretcher, the ends b' of these springs being held in a manner free to slide within the eyes or rings B', and being upturned, as at b', to prevent their withdrawal from such eyes. The enlarged upper portion of the holes in 35 which the ends are held permit a slight movement of such parts of the wires. To the opposite ends of the board A, which is convex, the strip or flap a', having concaved edge, is attached by means of the hinges a, prefer- 40 ably located upon the side edges of the board and strip, but which may, if desired, be placed in other position. The strap or flap A' is, as will be seen, somewhat broader than the board, and is provided upon its front edge with the 45 long groove a', to receive the clamp-wire C, and upon its side edges with the double grooves a'', the function of which is to receive the side bars of a plaiting-frame, which I have reserved to form the subject-matter of a sepa-

rate application. This clamping-wire, which 50 is of steel, is bent, as shown, and has its ends c driven obliquely into the side edges of the board; and, as will be noticed, the outer portions of the holes which receive the ends of the clamp-wire C are somewhat larger than 55 this wire, so as to permit its slight movement as it is drawn forward by the hinged flap.

From the foregoing construction it will be seen that when the hinged flap is turned back at an angle to the board the ends c of the 60 clamp-wire are in the rear of the enlarged sockets; but when the flap, with the clamp-wire thereon, is turned down into the plane of the board the wire is drawn slightly forward and exerts pressure upon the edge of the 65 flap.

The operation of the mechanism thus far described is as follows: The board A is placed inside the shirt, the collar-band of which is buttoned, and is drawn down over the collar-band- 70 stretching wires B and the bosom is smoothly laid upon the board. The clamp-wire C is now turned into a vertical position and the goods are drawn tightly over the same and down to the board, when the hinged flap is raised and the 75 clamp-wire, with the goods around it, is pressed into the groove of the front edge. As the flap and clamp-wire, with the goods firmly held thereby, are now turned toward a horizontal position, a tension is exerted upon the 80 shirt-front, which is increased until the flap is in plane with the board, and the bosom is stretched tightly thereon, ready to be ironed.

Having thus described my invention, what I 85 claim as new, and desire to secure by Letters Patent, is—

1. The combination, with the body of the board, of the flap hinged thereto, and having a grooved front edge and a pivoted clamp-wire, substantially as described. 90

2. The combination, with the body of the board, of the flap hinged thereto, and a wire having its ends pivotally connected to the body of the board, said wire forming a clamp for the flap, substantially as described. 95

3. The combination, with the body of the board, of the flap hinged thereto, and a clamp-wire having its ends driven obliquely into

the board, said board being cut away near the ends of said wire, substantially as and for the purposes set forth.

4. The combination, with the board and the 5 eyes or sockets, of the wires B, bent substantially as shown, and having their inner ends embedded in the board and their outer ends upturned and movably held in the eyes, substantially as described.

In testimony whereof I have hereunto set to my hand this 3d day of April, A. D. 1883.

ROBERT W. FERGUSON.

In presence of—

S. F. GREER,
L. F. SKELLEY.
